UNITED STATES PATENT OFFICE.

HENRY O. COSTELLO, OF PROVIDENCE, RHODE ISLAND.

RUNWAY.

Application filed May 9, 1923. Serial No. 637,856.

To all whom it may concern:

Be it known that I, HENRY O. COSTELLO, a citizen of the United States, residing at Providence, in the county of Providence and

5 State of Rhode Island, have invented certain new and useful Improvements in Runways, of which the following is a specification.

This invention relates to an improved runway for lifting one end of a vehicle, and has for its object to provide a runway or lift of this character comprising a pair of cooperating frames of a length less than that of the vehicle which they are designed to 15 lift and support, each frame having a horizontal rest portion raised a substantial distance above its base and provided with an inclined runway portion up which a wheel of the vehicle is run for the purpose of lifting the end of the vehicle sufficiently to 20 render it more accessible for inspection and repairs.

The invention further consists in removably mounting stop lugs at one or both ends 25 of the raised portion of the runway.

A further object of the invention is to form these runway members separately and independently whereby when not in use they may be stacked one upon the other to reduce 30 their space to the minimum for storage and transportation.

With these and other objects in view, the invention consists of certain novel features of construction, as will be more fully described, and particularly pointed out in the appended claims.

In the accompanying drawings:

Figure 1 is a perspective view showing one end of a vehicle as having been raised 40 by means of my improved runway.

Figure 2 is a perspective view showing one end of my improved runway.

Figure 3 is a sectional side elevation showing a portion of one of the runways being 45 slotted at opposite ends of its rest portion, and stop lugs mounted in said slots.

Figure 4 is a perspective view of the forward lug removed.

Figure 5 is a perspective view of the rear 50 lug removed.

It is found in practice of advantage to provide a pair of cooperating runways for lifting one end of an automobile and to form these runways of a length considerably less than the length of an ordinary automobile, the runways being formed sepa-

rately to work in pairs, the two being adapted when not in use to be stacked one upon the other to take up the minimum amount of space for storage and transportation. 60

It is also found of advantage to provide removable stop lugs at either end of the raised portion of these runways, which may be readily positioned both forwardly and rearwardly of the wheel when resting upon the runway, to lock the wheel against being accidentally rolled either forward or back thereon; also, by rendering these stop lugs removable the cost of production is reduced and also the storage room required for the 70 runway is reduced to the minimum; and the following is a detailed description of one construction of such runway by which these results may be accomplished.

With reference to the drawings, 10 designates the substantially horizontal portion of the frame of the runway, which is raised a substantial distance above the base portion on a plurality of legs which are spread apart at their bases and an inclined portion 75 12 of the runway is formed to lead from the base up to the horizontal or raised portion thereof, the entering end 13 of this inclined portion being flaring and grooved so as to guide the entering wheel up into the 80 12 of the runway. The entering end 13 is formed to lead from the base up to the horizontal or raised portion thereof, the entering end 13 of this inclined portion being flaring and grooved so as to guide the entering wheel up into the 85 12 of the runway.

The forward end of this horizontal portion is provided with a slot 14 into which a lug member 15 is set. This lug member is provided with a neck portion 16 adapted 90 to fit down into this slot, the same having a forwardly extending under lip 17 to project beneath the under side of the horizontal portion and is provided with an elongated upwardly and forwardly extending portion 95 18 which is curved outwardly to receive the periphery of the wheel, and spaced a short distance forward on a supporting base portion from the neck portion 16 is a downwardly extending flange 19 which rests 100 against the front surface of the runway providing a secure rest or support for the stop to resist any pressure which may be brought down upon it by the entering wheel. To further strengthen this leg 15 and its flange 19, I have formed a rib 20 leading from the outer end of the lug to the lower portion of this supporting rib. 105

Near the rear of this horizontal portion of the runway, I have formed another slot 110 21 and have provided a rear stop 22 having a neck portion 23 which extends down

through its slot and a forwardly extending lip portion which extends beneath the horizontal portion of the runway. This stop is also provided with a rearwardly extending shoulder or rest portion 25 which serves as a rest to support the upwardly-extending portion of the lug against any pressure which may be brought upon it by a backward motion of the wheel of the vehicle which may be mounted thereon.

My improved runway is very simple and practical in construction and effective in its operation and a pair of these devices may be used for raising either the forward or the rear end, and when not in use may be removed to be stored requiring but the minimum amount of space.

The foregoing description is directed solely towards the construction illustrated, but I desire it to be understood that I reserve the privilege of resorting to all the mechani-

cal changes to which the device is susceptible, the invention being defined and limited only by the terms of the appended claim.

I claim:

A vehicle-end lifting runway comprising a pair of cooperating frames, each of a length less than that of the vehicle one end of which the pair are designed to support, each frame having a short horizontal rest portion raised a substantial distance above its base for the reception of one wheel of the vehicle and a grooved inclined runway portion leading up to said rest portion, the opposite ends of said rest portion being slotted, and a pair of stop arms each having a locking lip adapted to enter its slot, and a rest shoulder on the back of said arms to support the same in set position.

In testimony whereof I affix my signature.

HENRY O. COSTELLO.
